PORTABLE COVER

Herman McCurley, deceased, late of Gary, Ind.,
by Mable M. McCurley, administratrix, Gary,
Ind.

Application May 1, 1939, Serial No. 271,208

4 Claims. (Cl. 105—377)

This invention relates to portable covers designed for use in connection with open or gondola freight cars, the primary object of the invention being to provide a rack or support for a removable cover of this character, which may be readily and easily mounted on the upper edge of an open freight car, without special tools or the services of a mechanic.

An important object of the invention is to provide a rack or support of this character which may be securely held in an upright position to support the canvas strip constituting the portable cover, means being provided for securing the rack or support in position.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawings:

Figure 1 is an elevational view illustrating racks and supports, constructed in accordance with the invention as supporting a canvas cover for an open freight car.

Figure 2 is a transverse sectional view through the body of the car, equipped with racks or supports constructed in accordance with the invention.

Figure 3 is an enlarged elevational view illustrating one of the racks or supports.

Figure 4 is a sectional view taken on line 4—4 of Figure 3.

Figure 5 is a sectional view taken on line 5—5 of Figure 3.

Referring to the drawings in detail, the rack or support embodies a main post 5 which is constructed preferably of metal bar material, the lower end of the support being extended at right angles as at 6, providing a brace to support the lower end of the post.

Secured to the lower end of the post 5, is a length of metal 7 riveted to the post 5, by means of rivets 8, the lower end of the length of metal extending laterally in a direction opposite to the laterally extended portion 6, providing a brace 9.

Secured to the members 6 and 9, is an inverted U-shaped clamp 10, which is formed with threaded openings near the free ends thereof, to receive the set screws 11. These inverted U-shaped clamps are adapted to be positioned over the upper edge of an open gondola freight car, and

the set screws 11 are provided to closely engage the sides of the open gondola freight car, securing the post 5 in its upright position.

Riveted, or otherwise secured to the upper edge of the post 5, is a U-shaped bracket 12, the bracket 12 having openings for the reception of the pin 13. The pin 13 is designed for restricting vertical movement of the supporting bar 14, over which the canvas forming the removable cover, is held.

The member 14 is constructed of telescoping members, whereby the member may be adjusted to various lengths.

Hooks indicated at 15 are supported at the upper end of the post 5, and afford means for hooking canvas sheets to the support, to protect the sides of the car, against the elements entering between the portable cover and upper edge of the freight car.

In the use of the device, it is contemplated to position several of the racks or supports along the edges of the gondola freight car, at predetermined distances apart. Bars are now positioned within the U-shaped brackets 12, as shown by the drawings, and sheets of canvas are now stretched over the bars and secured by means of the hooks 15, that extend through the brackets 12. Side canvas sheets indicated at 16 may be held in position by the hooks 15 carried by the post 5, thereby to protect the open sides of the car against the elements.

From the foregoing it will be seen that due to the construction shown and described, a portable cover has been provided for freight cars of the open type, so that men working within the open freight cars, may be protected against the elements.

What is claimed is:

1. A portable top for open cars, comprising upright supports, means for removably securing the supports over the upper edge of an open car, brackets on the upper ends of the upright supports, spanning bars removably held in the brackets, and canvas strips adapted to be positioned over the bars covering the open side of the car.

2. A portable top for open cars, comprising supports, adapted to be secured in spaced relation with each other, along the upper edges of an open freight car, each of said supports comprising a post, means at the lower end of each post for securing the post to the upper edge of a freight car, a U-shaped bracket at the upper end of each post, spanning bars adapted to be positioned within the U-shaped brackets, hooks on the supports,

and sheets of canvas material adapted to be stretched over the bars and secured by said hooks.

3. A portable top for open cars comprising upright supports, means for removably securing the supports to the upper edges of an open freight car, brackets at the upper ends of the supports, telescoping bars adapted to rest in the brackets, a length of canvas material adapted to be positioned over the telescoping bars providing a removable cover for the freight car, and hooks for securing the canvas cover in position.

4. A portable top for open cars comprising upright supports, means for removably securing the

supports to the upper edges of an open freight car, brackets at the upper ends of the supports, each of said brackets comprising a substantially U-shaped member, telescoping supporting bars resting on the brackets, said U-shaped members having aligning openings, and securing pins adapted to be extended through the openings in engagement with the bars held therein, securing the bars within the U-shaped members, and a canvas covering adapted to be stretched over said bars.

MABLE M. McCURLEY,
Administratrix of the Estate of Herman McCurley, Deceased.
